N. Y.

Application June 21, 1949, Serial No. 100,318

14 Claims. (CL 292—92)

1

This invention relates to locks for refrigerator doors or other closures. Such locks have been known which comprise a keeper fixed to a door jamb and a casing fixed to the door and including a spring pressed latch on the casing to engage the keeper, and a pivoted handle on the casing to retract the latch to permit the door to open.

It has also been known to provide such locks with means for pivotally moving the handle from the inside of the refrigerator so that if a person enters the refrigerator he can open the lock from within to permit him to open the door. Such locks have furthermore been so constructed that the handle is provided with an opening and the casing is provided with an opening registering with the opening in the handle when the handle is normally in the locking position of the lock. The purpose of these registering openings is to receive a padlock so as to permit locking the lock at the end of the day.

It has also been known that thieves sometimes enter a store which has such a refrigerator lock and force the proprietor to get into the refrigerator. Then they drop a headed pin or nail through the registering opening and make it impossible for the storekeeper to open the door from the inside, as the headed pin or nail prevents the handle from being pivotally moved. Various means have been devised to permit opening of the door from the inside of the refrigerator, notwithstanding the fact that a pin or nail has been inserted into the registering openings, but such previous constructions necessitated difficult manipulations, such as screwing of threaded members, which is not easy for one who is locked in a cold refrigerator. Sometimes such a lock is on a refrigerator which is quite small and does not give the person trapped therein much room to use tools for unscrewing various bolts as provided heretofore.

It is, therefore, an object of the present invention to provide a highly improved and simplified and easily manipulated means for retracting the spring pressed latch from the inside of the refrigerator even if the handle is locked in place by the insertion of a pin or nail or even a padlock through the registering openings in the handle and in the lock casing.

Another object of this invention is to provide a lock of the character described, including means to prevent retraction of the latch from the outside when the handle is bolted against pivotal movement.

Yet another object of this invention is to pro-

2

vide a strong, rugged and durable lock of the character described, which shall be relatively inexpensive to manufacture, easy to manipulate, which shall be sure and positive in operation, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which are shown various possible illustrative embodiments of this invention,

Fig. 1 is a longitudinal cross sectional view through a door and door jamb provided with a lock embodying the invention, and showing the handle locked against opening movement, and showing the latch engaging the keeper;

Fig. 2 is a view similar to Fig. 1, but illustrating the retraction of the latch from the inside of the refrigerator;

Fig. 3 is a cross sectional view similar to Fig. 1 but showing the lock handle pulled to retract the latch;

Fig. 4 is a top plan view of the lock;

Fig. 5 is a view of the inside of the lock attached to the refrigerator door;

Fig. 6 is an elevational view of the handle at the inside of the refrigerator door, employed for opening the lock;

Fig. 7 is an enlarged cross sectional view taken on line 7—7 of Fig. 1;

Fig. 8 is an enlarged cross sectional view taken on line 8—8 of Fig. 1;

Fig. 9 is an enlarged cross sectional view taken on line 9—9 of Fig. 1.

Referring now in detail to the drawings, 10 designates a refrigerator door and 11 a door jamb for said door. The door jamb has a front surface 12. The door 10 has an outer surface 13 and an inner surface 14. It is formed with an edge portion 15 which overlaps the door jamb and contacts a gasket 16 on the door jamb. Attached to the outer surface 12 of the door jamb is a keeper 17 of any usual construction and including a strike 18 of usual construction.

The door 10 is formed with a horizontal through opening 20 for the purpose hereinafter appearing. Attached to the outer surface 13 of the door 10 is a lock 21 embodying the invention, and adapted to cooperate with the keeper 17. The lock 21 comprises a lock casing 22. Said

50
45
55

casing 22 comprises a pair of spaced flanges 23 contacting the surface 13 of the door and each are formed with a plurality of apertures to receive screws 24, or other fastening members for attaching the casing to the door. Extending from the flanges 23 are a pair of side walls 25 interconnected by an outer wall 26 from the rear end of which extends a back wall 27. The casing is open at its front end. The side walls 25 may be tapered toward each other and toward the rear, thus being closer together at the rear than at the front.

At the forward end of the casing, the side walls have upwardly and forwardly projecting ears 28 formed with inclined forward edges 29.

At the forward ends of the ears 28 are spaced tongues 30. The ears 28 are formed with aligned openings 31 carrying a transverse horizontal pivot pin 32 formed with heads 33 at the ends thereof contacting the outer surfaces of said portions 28. Extending downwardly from the outer wall 26 is a lug 34 formed with a tapered through opening 35, for the purpose hereinafter appearing.

Adjacent the rear ends of the side walls 25 are formed through openings 36 through which extends a transverse pivot pin 37 formed at the ends thereof with rivet heads 38 contacting the outer side surface of said side walls. The purpose of the pivot pin 37 will be described hereinafter.

The under surfaces of the flanges 23 are grooved and engaged within the grooves is a transverse bottom plate 40 attached to the flanges by suitable screws or other fastening means.

The outer wall 26 terminates as at 43 rearwardly of the portion 28 of said side walls 25. However, extending from the top wall 26 and beyond the forward edge 43 are a pair of spaced upwardly extending ears 45 and 46, separated by a slot 47. Between the ear 45 and the adjacent side wall 25 is a slot 48 formed in the inner face of the adjoining wall 25. Between the ear 46 and the adjacent side wall 25 is a similar slot 49.

The ears 45 and 46 are formed with aligned openings 45a and 46a, respectively. Said ears are located outside the outer wall 26 so as to be exposed thereabove.

Pivoted to the transverse pin 32 is a latch member 50. Said latch member 50 is disposed between portions 28 of the lock casing. It has at its outer end a forwardly extending tapering tongue 51. It is formed with a through opening 52 through which the pivot pin 32 passes. Extending inwardly and rearwardly from the tongue 51 is a portion 53 formed at its rear surface with a notch 54. Traversing said notch is a horizontal pivot pin 55, the ends whereof are received in openings in the latch at opposite sides of the notch. Extending forwardly of the inner end of the latch are a pair of spaced apertured ears 57 carrying a transverse pivot pin 58 on which is mounted a roller 59.

When the latch is in normal unretracted position, as shown in Fig. 1, the roller 59 is adapted to engage the underside of the strike 18 to keep the door locked. When the door is locked as shown in Fig. 1, the tongue 51 is spaced outside the outer end 17a of the keeper. When the latch 50 is retracted by swinging the latch in a counterclockwise direction, from the position shown in Fig. 1 to the position shown in Fig. 2, the roller 59 will become disengaged from the strike 18 and the tongue 51 will move against the shoulder 17a

which limits its movement, and in such position the door can be opened.

Handle means is provided to swing said latch in a counterclockwise direction, looking at Fig. 1, for opening the lock. To this end there is pivoted to the pivot pin 32 a handle 60. Handle 60 has a pair of spaced side walls 61 formed with through openings 62 through which the pivot pin 32 passes. Said parallel walls 61 are received between the upper end of the latch 50 and the inner surfaces of portions 28 of the lock casing. Said side walls 61 are furthermore formed with aligned openings 64 adapted to register with the openings 45a, 46a when the handle is released and the door is locked. The loop or bolt of a padlock may be passed through the registering openings 45a, 46a and 64 to prevent the handle from being pivoted about the pivot 32. The forward end of the handle is hollow as shown in the drawing.

Extending from the hollow portion is a hand grip portion 65. At the forward end of the handle is a top wall 66 formed with an under edge 67 contacted by the tongue 51 of the latch 50. Thus, when the hand grip 65 is engaged and the handle pivoted in a counterclockwise direction about pivot 32, shoulder 67 will engage tongue 51 and cause the latch 50 to be rotated likewise in a counterclockwise direction to release the roller 59 from the strike 18, so that the door can be opened.

Means is provided to resiliently press the latch 50 in a clockwise direction towards the locking position. To this end, there is pivoted to the pivot pin 55 a bar 70 formed with a shoulder 71 and with a rearwardly extending reduced portion 72 passing through the opening 35 in the lug 34. On the bar portion 72 and between the shoulder 71 and the lug 34 is a coil compression spring 73 which normally tends to move the bar 70 to the left, looking at Fig. 1, for rotating the latch 50 in a clockwise direction. For the purpose hereinafter appearing, the under edge of the forward portion of bar 70 is formed with a curved notch 75. Thus, if the handle grip 65 is grasped and the handle pivoted in a counterclockwise direction, the latch 50 will be likewise rotated in a counterclockwise direction and retracted, but when the handle is released, the spring 73 rotates the latch in a clockwise direction and the tongue 51 pressing against shoulder 67 of the handle likewise rotates the handle in a clockwise direction about the pivot pin 32.

Means is provided to prevent rotation of the latch 50 in a counterclockwise direction by pushing an instrument against the roller 59. To this end, there is pivoted to the pivot pin 55 a bell crank 80 having an upwardly extending arm 81 formed at its rear surface with a notch 82 adapted to register with the openings 45a, 46a, and 64 of the handle. Said arm 81 may move through the slot 47 formed between the apertured ears 45 and 46 of the casing.

Extending rearwardly from the inner end of arm 81 is a second arm 83 integrally formed with the arm 81 and having an inner edge 84 normally disposed below the notch 75. If a bolt of a padlock is put through the openings 45a, 46a and 64, said bolt will be engaged by the notch 82, and if pressure is exerted rearwardly against roller 59, the latch 50 will be prevented from rotating in a counterclockwise direction by reason of the fact that the bolt of the padlock is within the notch 82, so that arm 81 cannot be moved longitudinally thereof. Thus, the safety feature

of the lock is preserved and the lock cannot be opened either by moving the handle 60 or by pushing with an instrument against the latch 50 when the lock is padlocked.

About pin 55 is a torsion spring 59 which tends to rotate the bell crank 80 in a clockwise direction, looking at Fig. 1 of the drawing, so as to cause the notch 82 to become aligned with the registering openings 45a, 46a and 64.

Means is provided, however, to retract latch 50 and open the lock from the inside of the refrigerator even if the lock is padlocked or if a headed pin or nail 90 is dropped through the openings 45a, 46a, and 64 and through the notch 82 of the arm 81.

To this end there is fixed to the inner surface 14 of the door 10 a bracket 91. The bracket 91 may be fixed to the door by means of screws 92. Said bracket 91 is formed with an opening 93 registering with the openings 20 and 41. Extending from bracket 91 are a pair of parallel apertured ears 94 carrying a transverse pivot pin 95, for the purpose hereinafter appearing. Also extending from bracket 91 are a pair of spaced parallel guide ears 96 in alignment with the apertured ears 94.

Pivoted to the pivot pin 95 is a handle 97. Handle 97 may have an outer wall 98 and side walls 99. The side walls 99 are disposed between the apertured ears 94 and between the guide ears 96. Said side walls or flanges 99 are formed with openings through which pivot pin 95 passes. Extending through the registering openings 93, 20 and 41 is a pin or rod 100, for the purpose hereinafter appearing.

Pivoted to the pivot pin 37 on the casing 21 is a lever 101. Said lever 101 has an inner wall 102 and side flanges 103 extending therefrom. Flanges 103 are formed with openings through which the pivot pin 37 passes. The inner wall 102 is adapted to contact the outer surface 13 of the door. It is formed with a rearwardly recessed portion 105 offset to receive the plate 40 and the flange 42. The portion 105 thus overlies the opening 41 in the flange 42 of plate 40.

The pin 100 is disposed between the pivot pin 95 and the outer end of the handle 97. When the outer end of the handle 97 is pressed towards the door 10, the pin 100 engages the offset portion 105 of the lever 101 and causes said lever to be rotated in a clockwise direction, looking at Fig. 1, about the pivot pin 37.

Interconnecting the forward ends of the flanges 103 is a pin 107 on which is mounted a roller 108 located between said side flanges. The roller 108 is located adjacent the notch 75 and normally contacts the under edge 84 of arm 83 of bell crank 80. When the handle 97 is pressed towards the door 10 to rotate said handle in a counterclockwise direction about the pivot pin 95, looking at Fig. 1 of the drawing, the lever 101 will be rotated in a clockwise direction about the pivot pin 37, and the roller 108 will rotate the bell crank 80 in a counterclockwise direction, moving the arm 81 to a position where the notch 82 no longer registers with the openings 45a, 46a, and 64. Further movement of the lever 101 will then cause the roller 108 to contact the notch edge 75 of member 70, and cause said member to be retracted or moved to the right, looking at Fig. 1, thereby compressing spring 78 and causing the latch 50 to be retracted or pivotally moved in a counterclockwise direction to disengage the roller 59 from the strike 18. Such movement is permitted because the arm 81 has been moved in a counter-

clockwise direction and even if the pin 90 were inserted through the openings 45a, 46a, and 64, the arm would first move to a position where the pin is disengaged, thereby permitting said arm 81 to move upwardly. Thus, it will be seen that even if a pin were inserted through the openings 45a, 46a, and 64, the latch may nevertheless be retracted from the inside of the refrigerator by pressing against the handle 97.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to protect by Letters Patent of the United States:

1. In combination, a lock casing adapted to be fixed to a door, a handle pivoted to said casing, said casing and handle being formed with registering openings, a latch pivoted to said casing and movable independently of said handle, means on the handle to rotate said latch for retracting the same upon swinging said handle in one direction, means operable from the inside of the door to retract said latch independently of said handle, means to prevent retraction of said latch upon inserting a member through said registering openings, and means effective upon operating the means operable from the inside of the door for releasing said preventing means.

2. In combination, a lock casing, means to fix said casing to the outside of a door, a handle pivoted to said casing, said handle and casing being formed with registering openings to receive a pin or a bolt of a padlock, a latch pivoted to said casing, means on the handle to swing said latch in one direction for retracting the same upon swinging said handle about its pivot, a lever within the casing, means adapted to be located at the inside of the door, for rotating said lever, means on the lever to retract said latch, means on said latch adapted to engage a pin or bolt of a padlock inserted through said registering openings to prevent retraction of said latch by pushing against the latch from the outside of the door, and means effective upon rotating said lever, for releasing said preventing means whereby to permit retraction of said latch upon rotating said lever.

3. In combination, a casing, a handle pivoted to the casing, a latch pivoted to the casing, means on the handle to swing said latch for retracting the same upon rotating said handle, spring means for projecting said latch, said casing and handle being formed with registering openings to receive a pin or bolt to prevent rotation of the handle relative to the casing, a member pivoted to the latch and having a hook engageable with a pin or bolt of a padlock inserted through said registering openings, a lever pivoted within said casing, and means effective upon rotating said lever for swinging said pivoted member to disengage the same from a pin or padlock bolt in said registering openings, and means also effective upon rotating said lever for retracting said latch.

4. In combination, a casing, a handle pivoted to the casing, a latch pivoted to the casing, means

on the handle to swing said latch for retracting the same upon rotating said handle, spring means for projecting said latch, said casing and handle being formed with registering openings to receive a pin or bolt to prevent rotation of the handle relative to the casing, a member pivoted to the latch and having a hook engageable with a pin or bolt of a padlock inserted through said registering openings, a lever pivoted within said casing, and means effective upon rotating said lever for swinging said pivoted member to disengage the same from a pin or bolt of a padlock in said registering openings, means also effective upon rotating said lever for retracting said latch, and means for rotating said lever.

5. In combination, a lock casing, a handle pivoted to the casing, a latch pivoted to the casing about the same axis as the handle, said latch being formed with a tongue, said handle being formed with a shoulder engageable with said tongue whereby upon said rotation of said handle, the said latch will be rotated in one direction, a strike engaging means on said latch adapted to be retracted upon swinging said handle, spring means for projecting said latch, said handle and casing being formed with registering openings adapted to receive a pin or a bolt of a padlock, a bell crank pivoted to said latch, said bell crank having one arm formed with a notch adapted to receive a pin or the bolt of a padlock inserted through said registering openings, a lever pivoted within said casing, said bell crank having a second arm engageable by the free end of said lever, whereby rotation of the lever will rotate said bell crank in a direction for disengaging the first arm of the bell crank from a pin or bolt of a padlock inserted through said openings, and means effective upon rotating said lever for retracting said latch against said spring means.

6. In combination, a lock casing, a handle pivoted to the casing, a latch pivoted to the casing about the same axis as the handle, said latch being formed with a tongue, said handle being formed with a shoulder engageable with said tongue whereby upon said rotation of said handle, the said latch will be rotated in one direction, a strike engaging means on said latch adapted to be retracted upon swinging said handle, spring means for projecting said latch, said handle and casing being formed with registering openings adapted to receive a pin or a bolt of a padlock, a bell crank pivoted to said latch, said bell crank having one arm formed with a notch adapted to receive a pin or the bolt of a padlock inserted through said registering openings, a lever pivoted within said casing, said bell crank having a second arm engageable by the free end of said lever, whereby rotation of the lever will rotate said bell crank in a direction for disengaging the first arm of the bell crank from a pin or bolt of a padlock inserted through said openings, means effective upon rotating said lever for retracting said latch against said spring means, and means to rotate said bell crank in an opposite direction.

7. In combination, a casing adapted to be attached to the outside of a door, said casing being formed with an opening, handle means movably mounted on the casing, said handle means having an opening registering with the opening in the casing whereby the bolt of a padlock or a pin may be inserted through said registering openings to prevent movement of the handle means relative to the lock casing, latch means mounted on said

casing for movement independently of the handle means, spring means to project said latch means, said handle means having means to retract said latch means upon moving said handle means relative to said lock casing, means actuatable from the inside of the door for retracting said latch means while the handle means is locked to the casing, and means on said latch means engageable with the bolt of a padlock or a pin inserted through said registering openings to prevent retraction of said latch means.

8. In combination, a casing adapted to be attached to the outside of a door, said casing being formed with an opening, handle means movably mounted on the casing, said handle means having an opening registering with the opening in the casing whereby the bolt of a padlock or a pin may be inserted through said registering openings to prevent movement of the handle means relative to the lock casing, latch means mounted on said casing for movement independently of the handle means, spring means to project said latch means, said handle means having means to retract said latch means upon moving said handle means relative to said lock casing, means actuatable from the inside of the door for retracting said latch means while the handle means is locked to the casing, means on said latch means engageable with the bolt of a padlock or a pin inserted through said registering openings to prevent retraction of said latch means, and means operable by the means actuatable from the inside of the door for releasing the preventing means from engagement with a bolt of a padlock or a pin inserted through said registering openings whereby to permit retraction of said latch means upon actuating said means actuatable from the inside of the door.

9. In combination, a lock casing, a handle pivoted to the casing, a latch pivoted to the casing, means on the handle to retract the lock upon swinging the handle, a member pivoted to the latch and disposed within the casing, spring means for pushing said member in a direction for swinging said latch to projected position, said handle and casing being formed with registering openings, a member pivoted to the latch and having a hook adapted to engage the bolt of a padlock or a pin inserted through said openings, and a lever pivoted within said casing, and means on the lever operable upon rotating the lever in one direction for releasing the hook on the member pivoted to the latch from engagement with the bolt of a padlock or a pin inserted through said registering openings and upon further rotation of said lever in the same direction, to engage the spring pressed member and move the same in a direction for retracting the latch.

10. In combination a lock casing adapted to be fixed to the outside of a door, a handle pivoted to said lock casing, a latch pivoted to said lock casing and movable independently of said handle and relative thereto, means effective upon rotating the handle for retracting the latch, a lever pivoted within said casing, means for retracting the latch independently of the handle, upon rotating said lever, means to lock the handle to the casing, releasable means cooperable with said handle locking means to retain said latch against retraction, means cooperating with said lever to release said retaining means to permit retraction of said latch, and means operative from the inside of the door for rotating said lever to retract said latch.

11. The combination of claim 10, in combination with spring means to project said latch.

12. The combination of claim 10, said means operative from the inside of the door, comprising a handle adapted to be pivoted to the inside of the door, a member adapted to extend through an opening in the door and interposed between said inside handle and said lever whereby upon rotating said inside handle, said lever will be rotated about its pivot for releasing said retaining means and retracting said latch.

13. In combination, a lock casing adapted to be attached to the outside of a door, handle means movably mounted on the casing, means to lock said handle means to said casing, latch means mounted on the casing for movement independently of the handle means, said handle means having means to retract said latch means upon moving said handle means relative to said lock casing, means actuatable from the inside of the door for retracting said latch means while the handle means is locked to the casing, means co-operable with said handle locking means to releasably retain the latch means against retraction, and means cooperable with the means for retracting the latch means from the inside of the door to release said retaining means to permit

10

5

retraction of the latch means for the inside of the door.

14. The combination of claim 13 in combination with spring means to project said latch means.

ALFRED H. GROEGER.
